(57) **CLAIM**

The ornamental design for a noise dosimetry, as shown and described.

DESCRIPTION

FIG. 1 is a perspective view of a noise dosimetry showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof, wherein the buttons are covered by a transparent cover that prevents inadvertently touching the buttons; and,

FIG. 9 is an exploded perspective view thereof, wherein the transparent cover is detached.

The broken lines are shown for illustrative purposes only and form no part of the claimed design.
